UNITED STATES PATENT OFFICE

LEONARD A. MACLEAN, OF READING, MASSACHUSETTS

PACKAGE FOR PATCHES

Application filed February 11, 1929. Serial No. 339,062.

This invention relates to gummed reinforcing patches adapted to be adhesively united to articles of sheet material, such as the leaves of a loose-leaf binder, shipping tags, etc., each patch being applied to an article in position to surround a hole therein.

The invention relates particularly to patches customarily applied one at a time by hand, like a postage stamp. Heretofore such patches have been marketed in a loose condition usually in a box or carton, and applied by separately handling each patch, which is moistened, usually by the tongue, to render the gummed side adhesive.

The object of my invention is to enable reinforcing patches to be quickly and conveniently applied one by one without being separately handled, and in such manner as to make it more convenient for the user to render the gummed coatings adhesive by moisture applied by mechanical means than by the unsanitary use of the tongue.

In attaining this object I assemble a multiplicity of gummed patches on an elongated core in such manner as to form a dispensing package composed of a core and a body of patches mounted thereon, the package being operable to apply the patches one by one, an end patch of the body being detachable therefrom, when its gummed side is conditioned to adhere to the reinforced article, and the package is pressed endwise against the article, the body of patches being slideable on the core, so that after an end patch has been detached, another takes its place, there being no separate handling of any patch.

Of the accompanying drawings forming a part of this specification,—

Figure 1 is a side view, showing a dispensing package embodying the invention.

Figure 2 is a perspective view of the core.

Figure 3 is a view similar to Figure 1, showing a presser movable on the core and bearing on the body of patches.

Figure 4 is an enlarged section on line 4—4 of Figure 1.

Figure 5 is a perspective view, showing a patch partly broken away to show its gum coating.

Figures 6 and 7 are views similar to Figure 4, showing a modification.

Figure 8 shows the dispensing package combined with a supporting stand.

Figure 9 is a side view of a leaf for use with a loose leaf binder, and a patch reinforcing the portion of the sheet containing one of the usual holes therein.

The same reference characters indicate the same parts in all of the figures.

In the drawings, 12 designates a core which is preferably a metal tube adapted to enter the orifice 13 of an ordinary patch 14, said patch having on one side a gum coating 15. The length of the core is such that a multiplicity of patches may be strung on the core side by side to form a body which may contain several hundred patches of the thickness of those usually employed for reinforcing paper leaves, tags, etc.

The core has a receiving end, which is the upper end when the core is positioned as shown by Figure 1, and a delivering end provided with an enlargement adapted to so oppose endwise movement of the body toward the delivering end as to prevent accidental endwise movement of the body toward said end, and releasably hold the end patch flush with the delivering end, said enlargement being adapted to permit the forcible detachment of the end patch from the body and core when said patch is caused to adhere to an article reinforced thereby, as hereinafter described. Said enlargement is, in this instance, yielding and formed by cutting longitudinal slots in the tube, thereby forming tongues 16 which are bent outward, as shown by Figures 2 and 4. Said tongues are resilient and adapted to bear yieldingly on the inner margin of the end patch constituting the inner end of the body, and thus non-positively and frictionally oppose removal of said patch from the core.

The gummed sides of the patches face toward the delivering end of the core. The major portion of the core, extending from the delivering end to the receiving end, may be of such diameter that the patches can slide freely upon it. To prevent removal of the patches from the receiving end, I provide the latter

with a positive stop 17, which is removable from the core to permit the stringing of the patches thereon to form the body, said stop being preferably a nut engaged with a threaded end portion of the core.

5 In operating the described package, it is held vertically, and the body of patches is moved by pressure exerted on the end adjacent the receiving end of the core, until the 10 opposite end is flush with the outer ends of the core tongues 16, said tongues preventing the lowest patch from dropping off the core, the latter at the same time bearing on the article 18, or on a bed 25 supporting it.

15 The operator exerts endwise pressure on the body to move the same downward on the core and press the lowest patch against the article 18, said patch being caused to adhere to the article by moistening the gum coating 20 15, either by applying water thereto, or to the portion of the surface of the article which surrounds a hole therein. The final pressure exerted on the body forces the lowest patch from the core and leaves it on the article 18, when the package is lifted, the 25 lifting operation exerting sufficient force to detach the end patch from the core and the body.

30 The described operation may be repeated until all the patches have been applied and the body is exhausted.

The core may be thin metal tubing, costing so little that it may be discarded when the body is exhausted, the package formed by 25 the core and body constituting an article of merchandise, which may be bought like a box or carton of loose patches.

35 It will be seen that the patches composing the body require no separate handling, and are separable from each other, so that they may be rapidly and conveniently applied.

40 The body may be moved on the core either by pressure exerted directly on one end of the body, as indicated by Figure 1, or by an annular presser 21, movable on the core and bearing on one end of the body, as shown by Figure 3.

45 Figures 6 and 7 show a modified construction of the delivering end of the core. The resilient tongues formed by slotting the core, and here designated by 16a, are relatively thick at their outer ends, and gradually decrease in thickness so that the bore of the slotted core portion formed by the tongues is tapered and smallest at the end of the core. A 50 tapered plug 23, conforming to the bore of the slotted core portion, is pressed outwardly by a spring 24, and caused to normally press the tongues 16a outward and cause their outer 55 sides to frictionally engage the lowest patches of the body, as indicated by Figure 6. The plug projects from the core sufficiently to be forced into the core by contact with the bed 25, supporting the article 18, when the package 60 is moved from the position shown by Figure

6 to that shown by Figure 7. The movement of the plug thus caused permits the tongues 16a to spring inwardly, which is their natural tendency, thus causing their outer sides to release the lowest patches, as indicated by Figure 7, so that the patch when caused to adhere to the article 18, is separated from the body when the package is lifted. The lifting of the package permits the projection of the plug 23 by the spring 24, so that the tongues immediately reengage the lowest patches and oppose downward movement thereof.

65 The spring 24 may be supported by any suitable abutment fixed in the core, said abutment being formed, for example, by tongues 26 integral with the core and pressed into the bore thereof. The outer end of the plug 23 serves as a locating device to properly locate an applied patch with relation to a hole 19, the plug being inserted in the hole when it is pressed on the bed 25.

70 Figure 8 shows a supporting stand associated with the described package. Said holder includes a guide 27 supported by a standard 28 on a base 29, said guide being an arm having an orifice in which the core 12 is vertically movable. The bed 25 is supported above the base and adapted to support the article 18 in the path of the package, when the latter is moved downward. The base is provided with an article-locating projection 31, adapted to enter a hole 19 and locate the article 18 in position to receive a patch. The stand may be provided with means for moistening the upper side of the article 18, when the latter is held by the operator in the lower dotted line position shown by Figure 8, said means including a downwardly facing brush 32, supplied with water from a tank 33 by a wick 34 extending to the brush through a tube 35.

75 The package is yieldingly supported in a raised position by a spring 36 interposed between the guide 27 and the nut or stop 17, to permit the interposition of the article 18 between the bed and the package, the spring permitting the packages to be moved downward until the lowest patch is secured to the article 18, and then raising the package, as shown by Figure 8. The guide 27 may be pivoted at 38 to the standard 28, so that it may be swung upward to facilitate the insertion of the core 12 in the guide, and its removal therefrom.

80 It will be seen that in each of the described embodiments of the invention the delivering end of the core is provided with an enlargement releasably engaging the inner margin 125 of an end patch of the body to hold said patch flush with the delivering end, prevent accidental endwise movement of the body toward said end, and permit the forcible detachment of the end patch from the body 130

and core when said patch is caused to adhere to an article reinforced thereby.

The resistance offered by the enlargement to the detachment of the patch adhering to 5 the reinforced article, is so inconsiderable that there is no liability of the article being pulled away from the patch.

I claim:

1. A dispensing package comprising a 10 holder, patches designed for application to an object and superposed upon each other, means for retaining said patches in superposed relation, said means being movable relative to the holder as said patches are dispensed.

2. A dispensing package comprising a holder, a plurality of superposed annular gummed patches, said holder consisting of an elongated member extending through the 20 plurality of annular gummed patches, the elongated member being provided with means to prevent the accidental removal of the individual patches and a movable presser member, on the elongated member, adapted 25 to force the patches to their operative relation or position.

3. A dispensing package comprising a holder, a plurality of superposed annular gummed patches, said holder consisting of 30 an elongated tubular member extending through the plurality of annular gummed patches, the elongated tubular member being provided with means to prevent the accidental removal of the individual patches and 35 a slideable presser member, on the tubular elongated member, adapted to force the patches to their operative relation or position.

4. A kit comprising a supporting member 40 provided with guiding means, in combination with a dispensing package, said dispensing package comprising a holder, patches designed for application to an object, and superposed upon each other, said 45 holder including retaining means having a guiding element at one end and cooperative with said guiding means for properly placing the individual patches on an object on said supporting member.

5. A kit comprising a supporting member 50 having a nib or projection thereon in combination with a dispensing package, comprising a holder, patches designed for application to an object and superposed upon each other, said holder including retaining means having a cavity in one end portion; said means co-operating with the nib or projection on the supporting member for properly placing the patches.

6. A dispensing package comprising an elongated core having a receiving outer end and a delivering inner end, and a body composed of a multiplicity of annular gummed patches assembled side by side on the core 65 with their gummed sides facing the deliver-

ing end, the body being movable endwise on the core, the delivering end of the core being provided with a yielding enlargement composed of resilient tongues bearing yieldingly on the inner margin of an end patch of the body, and releasably holding said patch flush with the delivering end, preventing accidental endwise movement of the body from said end, and permitting the forcible detachment of the end patch from the body and 70 core, when said patch is caused to adhere to an article reinforced thereby.

7. A dispensing package comprising a holder and a plurality of superposed apertured gummed patches, said holder consisting of an elongated member extending through the patches, the holder being provided with means to prevent the accidental removal of the individual patches, one end of the group of superposed patches being exposed to receive pressure whereby said group 85 may be forced endwise on the holder.

In testimony whereof I have affixed my signature.
